UNITED STATES PATENT OFFICE.

THEODORE W. FOSTER, OF PROVIDENCE, RHODE ISLAND.

DESIGN FOR A COVER FOR PUFF-BOXES OR SIMILAR ARTICLES.

SPECIFICATION forming part of Design No. 31,120, dated July 4, 1899.

Application filed June 2, 1899. Serial No. 719,145. Term of patent 7 years.

To all whom it may concern:

Be it known that I, THEODORE W. FOSTER, of Providence, in the county of Providence and State of Rhode Island, have invented and produced a new and original Design for the Covers of Puff-Boxes or Similar Articles, of which the following is a specification, reference being had to the accompanying drawings, forming part thereof.

Figure 1 is a top view of a cover, showing my design. Fig. 2 is a sectional view of the same.

The leading feature of my design consists in the raised circular border having inwardly-curved scrolls from which wreaths of flowers extend in festoons, connected with a bunch of flowers supported on a shell.

In the drawings, A indicates the circular marginal border, composed of the two concentric rings *a a*, over which the leaf ornaments *b b*, springing from the marginal ring, extend. The scrolls *c c* extend from the circular border, curving inward near one side of the circular

cover. The fan-shaped ornament *d* fills in the space between the adjacent scrolls *c c* on one side of the cover, and the shell ornament *e*, presenting the appearance of a bowl, extends from the opposite side of the cover. The convex panel *f*, inclosed by the circular marginal border *A*, is ornamented by the floral festoons *g g* and the floral festoons *h h*, suspended from the scrolls *c c*, the ends of the floral festoons *h h* extending in a curve to the floral bouquet *i*, supported on the shell-shaped bowl *e*.

Having thus described my invention, what I claim as new, and desire to secure by Letters Patent, is—

The design for the cover of a puff-box or similar article herein shown and described.

In witness whereof I have hereunto set my hand.

THEODORE W. FOSTER.
